LOCK FOR GATES

Charles R. Dray, Rochester, N. Y.

Application April 16, 1943, Serial No. 483,290

6 Claims. (Cl. 292—148)

The object of this invention is to provide a new improved means for locking the end of one gate to the post or locking the ends of two gates together.

Another object of the invention is to lock the gate or gates with a bolt which bolt in turn can be locked in place in the lock with a padlock at one end or with a padlock at each end of the bolt.

Another object of the invention is to provide locking members on separate mounts which can be brought together for the purpose of locking them together and holding them together by a sliding bolt.

These and other objects of the invention will be illustrated in the drawings and described in the specification and pointed out in the claims at the end thereof.

In the drawings:

Figure 1 is a front elevation of the lock stile of two gates partly broken away showing the members of the lock mounted thereon and in locked position.

Figure 2 is a sectional view of Figure 1, the section being taken on the line 2x—2x of Figure 1, the chain being omitted.

Figure 3 is a vertical section on the line 3x—3x of Figure 2, the chain being omitted.

Figure 4 is a detail view of a locking bolt showing a padlock at each end of the bolt.

Figure 5 is a perspective view of a modified form of my locking device showing the locking members on the stiles of the gates made in the form of castings.

Figure 6 is a top plan view of a modified form of the part 21 which modification can also be applied to the part 22.

Figure 7 is a diagrammatic view of my locking device applied to a single sliding gate.

Figure 8 is a diagrammatic view of a double sliding gate.

Figure 9 shows a modified form of one of the locking members of Figure 5, namely, partly mutilated so that it can be used on a swinging gate swinging against a fixed post or on a swinging gate swinging against the stile of a fixed gate.

In the drawings like reference numerals indicate like parts.

In the drawings reference numerals 1 and 2 indicate the lock stiles on a pair of hinged or swinging gates or on a pair of sliding gates or on a pair of gates in which one is hinged and the other is sliding.

Reference numeral 3 indicates the male or

middle member of the lock and reference numerals 4 and 5 represent the outside or top and bottom members of the female member of the lock. The member 3 is a box-like structure formed of four separate plates, 3a and 3b being the side members and 3c and 3d being the top and bottom members. These four members are formed of sheet steel or any other suitable metal and are welded together so as to form a hollow box-like structure.

The members 3a and 3b are welded to the lock-stile 2 of the gate and the members 3c and 3d can also be welded to the lock stile of the gate. The horizontal members 3c and 3d are each perforated with a slot indicated at 3e.

Fastened to the lock stile 1 are the two plates 4 and 5 which plates stand horizontally at right angles thereto and are welded to the stile. These plates each have an opening preferably rectangular therein indicated at 4a and 5a. The plates 4 and 5 stand in parallel relation to the plates 3c and 3d when the gate is closed or the gates are closed and the holes 4a and 5a are located so that they will stand in line with the holes 3e of the middle member when the gate or gates are closed. It will also be seen from an inspection of Figures 1 and 3 that the members 4 and 5 are spaced apart much further than the height or the up and down dimension of the male member shown in Figure 3. This is to give ample clearance between the male and female members so that the parts can come properly together regardless of expansion or contraction due to heat or cold or regardless of the settling of the gates or regardless of wear and tear.

When the gates are brought together the parts and the holes therein will be in alignment as shown in Figures 1 and 3 and then the locking bolt can be passed through the openings in the male and female members.

This locking bolt is indicated by the reference numeral 6 and is preferably fastened to one of the gates by a chain 7 although this chain can be omitted. A rod 8 is preferably welded in the top of the bolt 6 and forms a cross bar which limits the downward movement of it. This cross bar rests on the plate 4 when the bolt is in locking position so that the bolt can not be pulled down through the female and male members of the lock. The bottom of the bolt 6 is perforated as indicated at 9 to receive the keeper of a padlock 10 by which the bolt is permanently locked in place so that the gates will be kept closed.

The plates 3a and 3b are flared outwardly at

the end as indicated at 3m and 3n. It is necessary to move both gates at the same time in closing the gates so that the lock stile 1 will engage between the flared ends 3m and 3n of the male members 3a and 3b and as the gates are swung into line with each other the lock stile 1 with its plates 4 and 5 moves into the position shown in Figures 2 and 3. This brings the holes 3e into line with the holes 4a and 5a so that the bolt 6 will easily pass through all the holes. It will also be understood that the lock stile 1 makes a rather close fit between the members 3a and 3b when the gates are closed.

In Figure 4 I have shown a locking member 12 in which the chain is omitted at the top and which member is perforated with a hole at the top and bottom. In this case padlocks 13 and 14 are used at the top and bottom respectively. The upper padlock 13 keeps the bolt from being pulled down through the lock and the lower padlock 14 prevents the bolt from being pulled up through the lock. These padlocks will be different so that the key that unlocks the one will not unlock the other and this is desirable so that the one padlock can be unlocked by railroad men or by the fire department or any other selected organization and the other lock can be unlocked by someone of the factory organization.

In Figure 5 I have shown the two members of the lock 21 and 22 which are equivalent to the female and male members shown in Figures 1, 2 and 3. In this case, however, the members 21 and 22 are each made in a separate piece as a solid casting. The member 21 has a sleeve 21a therein which makes a sliding fit with the lock stile 1 of its gate or post and the member 22 has a sleeve 22a therein which makes a sliding fit with the stile 2 of its gate or the post on which it is placed. Each of these members is welded or fastened in any other suitable manner to the stile or post that supports it. The sleeve 21a or 22a can be slid up and down and provided with extending flanges through which a bolt or bolts can extend by which it can be clamped on its stile at any desired elevation thus providing for adjustment made necessary by changing conditions. On the member 21 are provided the two tongues 21b and 21c corresponding to the members 4 and 5 in Figure 1 and on the member 22 is provided the box-like portion 22b having the flared ends 22c and 22d corresponding to the similar part of the corresponding part on the members 1, 2 and 3. Each of the parts 21b, 21c and 22b is provided with the opening through which extends the locking bolt similar to the bolt 6 shown in Figure 1 or the bolt 12 shown in Figure 4.

As shown in Figure 6 the member 25 similar to the part 21 can be formed with a slot as indicated at 26 with the flanges 27 and 28 thereon which can be brought together by a bolt and nut 29. The interior surface 30 of this member can be formed roughened in any suitable manner so as to obtain a better grip on the stile that supports it.

This method of mounting or clamping can also be applied to the member 22.

In Figure 7, I have shown the sliding gate 40 which gate slides beside the fence. In this case the male or the female member can be fastened on the lock stile of the sliding gate and the other member can be fastened on the post. The member on the post will have its sleeve on the side of the locking member as shown in Figure 7 instead of on the end of it as shown in

Figure 2 or Figure 5 so that the locking member comes in line with the travel of the gate.

In Figure 8 I have shown two sliding gates each of which travel parallel to the fence. These gates come together at the middle and use the locking devices shown in Figures 1, 2 and 3 or as shown in Figure 5. The gates may not necessarily be of equal length and each gate can be stopped in some suitable manner so that it cannot travel beyond its locked position.

In Figure 9 I have shown a diagrammatic view of a swinging gate in which the female locking member shown in Figures 2 and 5 is mutilated by having one of the extensions 3a or 3b in Figure 2 or one of the extensions 22c or 22d shown in Figure 5 omitted therefrom so that the gates may swing to closed position and be positively stopped in that position against a stationary post or against the stile of another gate which gate can be fastened independently in closed position in any suitable manner.

In such case the position of the male member and the female member of the lock can be reversed or alternated so that either gate can be opened independently.

It will also be understood from an inspection of several figures of the drawings that the upright members that carry the male and female members of the lock are suitably spaced apart when the gate or gates are closed and the operator can put his hand through between the upright members and reach the lock to unlock it from either side of the gate.

I claim:

1. In a lock for double gates said gates being placed in line with each other when closed the combination of a lock stile on each of two gates the said stiles being suitably spaced apart when the gates are in closed position, a female member having two horizontal plates fastened on the stile of one gate, a male member having two horizontal plates fastened on the stile of the other gate, the horizontal plates of the male member substantially spanning the opening between the two gates and extending between the two horizontal plates of the female member and extending toward the other gate, the male member having two upright plates enclosing the horizontal plates and extending beyond the horizontal plates of the member, and being adapted to embrace the stile of the other gate supporting the female member.

2. In a lock for double gates said gates being placed in line with each other when closed the combination of a lock stile on each of two gates the said stiles being suitably spaced apart when the gates are in closed position, a female member having two horizontal plates fastened on the stile of one gate, a male member having two horizontal plates fastened on the stile of the other gate, the horizontal plates of the male member substantially spanning the opening between the two gates and extending between the two horizontal plates of the female member and extending toward the other gate, the male member having two upright plates enclosing the horizontal plates and extending beyond the horizontal plates of the member, and being adapted to embrace the stile of the other gate supporting the female member, each of said members having a vertical hole extending therethrough, said holes standing in line with each other when the gates are closed, a locking bolt adapted to extend through the holes in both the male and female members and thereby locking the gates to

gether, means for locking the locking bolt in place in the male and female members.

3. In a lock for double gates the combination of a lock stile on each of two gates said stiles being suitably spaced apart when the gates are in closed position, a female member having two horizontal plates fastened on the stile of one gate, a male member having two horizontal plates fastened on the stile of the other gate, the horizontal plates of the male member substantially 5 spanning the opening between the two gates and extending between the two horizontal plates of the female member, the male member having two parallel plates standing in an upright position, the ends of said plates extending beyond the lock stile of the other gate and engaging said last named lock stile between them when the gates are in closed position.

4. In a lock for double gates the combination of a lock stile on each of two gates said stiles 20 being suitably spaced apart when the gates are in closed position, a female member having two horizontal plates fastened on the stile of one gate, a male member having two horizontal plates fastened on the stile of the other gate, the 25 horizontal plates of the male member substantially spanning the opening between the two gates and extending between the two horizontal plates of the female member, the male member having two parallel plates standing in an upright position, the ends of said plates extending beyond the lock stile of the other gate and engaging said last named lock stile between them when the gates are in closed position, the ends 30 of said plates flaring outwardly and extending beyond the last named lock stile.

5. In a lock for a gate the combination of an upright supporting member, a female locking

member supported thereon, an upright supporting member adjacent thereto, a male locking member supported thereon, the male locking member having two horizontal plates and two vertical plates formed in a box-like structure, the female member having two horizontal plates, all four of said horizontal plates having vertical holes therein, a locking bolt adapted to pass through the holes in the four horizontal plates 10 and lock the male and female members together said upright supporting members being suitably spaced apart with a substantial opening between them when the male and female members of the lock are brought together, the male member spanning the opening between the two upright supporting members and stopping short of the other supporting member, said parts being so arranged that the lock is accessible from either side of the gate through the opening between the upright members.

6. In a lock for a gate the combination of an upright supporting member, a female locking member supported thereon, an upright supporting member adjacent thereto, a male locking member supported thereon, the male locking member having two horizontal plates and two vertical plates formed in a box-like structure, the female member having two horizontal plates, all four of said horizontal plates having vertical holes therein, a locking bolt adapted to pass through the holes in the four horizontal plates and lock the male and female members together, the male member having upright outwardly flaring extensions thereon adapted to engage both sides of the supporting member of the female member.

CHARLES R. DRAY.
